UNITED STATES PATENT OFFICE

97,740

DESIGN FOR A RADIO DIAL WINDOW

Benjamin S. Nash, Short Hills, N. J., assignor to
Philco Radio & Television Corporation, Phila-
delphia, Pa., a corporation of Delaware

Application April 8, 1935, Serial No. 56,278

Term of patent 14 years

To all whom it may concern:

Be it known that I, Benjamin S. Nash, a citizen of the United States, residing in Short Hills, county of Essex, State of New Jersey, have invented a new, original, and ornamental Design for a Radio Dial Window, of which the following is a specification, reference being had to the accompanying drawing, forming part thereof, in which:—

Figure 1 is a face view of the radio dial window; and

Fig. 2 is a sectional view of the same taken on the line 2—2 of Fig. 1.

In Fig. 1, the portions of the window shown in solid black represent a metallic coating applied to the back of the transparent member to render such portions reflecting, while the stippled portion represents a ground section of the transparent member.

I claim:—

The ornamental design for a radio dial window, substantially as shown and described.

BENJAMIN S. NASH.
